UNITED STATES PATENT OFFICE.

CHARLES W. LOWE, OF JERSEY CITY, NEW JERSEY, ASSIGNOR TO WESTERN ELECTRIC COMPANY, INCORPORATED, OF NEW YORK, N. Y., A CORPORATION OF NEW YORK.

CONNECTOR.

1,309,253.

Specification of Letters Patent.

Patented July 8, 1919.

Application filed February 5, 1917. Serial No. 146,679.

To all whom it may concern:

Be it known that I, CHARLES W. LOWE, a citizen of the United States, residing at Jersey City, in the county of Hudson and State 5 of New Jersey, have invented certain new and useful Improvements in Connectors, of which the following is a full, clear, concise, and exact description.

This invention relates to connecting devices for use in electric circuits, and particularly to devices of the type wherein the circuit connections are established by means of plugs and jacks.

One object of the invention is the production of a connecting jack in which the contact members are constructed so as to provide the required flexibility but so disposed in their relation to their supports that they occupy a comparatively small space.

Another object is the production of a connector of the type wherein a plurality of plugs are used as a unit and in which the said plural plug unit is adapted to coöperate with a corresponding set of plural jacks, the 25 said connector being so constructed that the individual plugs are not held in a definite or fixed relation to each other, but a slight lateral movement is permitted whereby the said individual plugs of the unit will co-30 operate with plural jack sets in which the individual jacks are mounted on slightly varying centers.

The production of apparatus of this type has proved to be unsatisfactory heretofore 35 from a manufacturing standpoint, for the reason that both the plug and jack mountings have required accurate and expensive tools in order to avoid inaccuracies in the mounting centers, which objections have 40 been overcome in this improved apparatus.

This apparatus is particularly adapted for use in the equipment of large multiple telephone switchboards as a means of interconnection between the operator's telephone 45 set (transmitter and receiver) and the circuits of the switchboard, due in part to the fact that it occupies less space than apparatus used heretofore for the same purpose, and also due to the fact that it does not project 50 beyond the face of the switchboard when mounted for use, and in that way overcomes a serious objection from an operating standpoint to the apparatus used heretofore for the same purpose.

55 The various features of this invention will be more readily understood by reference to

the accompanying drawings, in which Figure 1 is a side elevation of the plug and jack partly in section; Fig. 2 is a bottom view of the apparatus with the parts interconnected into operative relation; and Fig. 3 is a side elevation of the apparatus with the parts interconnected into operative relation and illustrating the manner in which they are mounted in a switchboard. 65

Referring now to the drawings, the plug comprises a pair of connectors 5 and 6 the ends of which are inclosed in a shell or casting 1 open at one end and having a pair of rectangular brass strips 2 and 3 attached to 70 the inner top and bottom walls thereof by screws 4. The end of each connector is embedded in a rectangular block of insulating material 7 molded to the required form. Grooves molded on opposite sides of the insulating block engage the brass strips 2 and 3, and by means of said engagement the connectors and shell are interlocked. 75

The inside width of the shell 1 is slightly greater than the combined width of the two 80 blocks of insulating material on the connectors, which permits the said connectors to move longitudinally, either individually or collectively, a distance equal to this difference. Each connector is shown as comprising two contact portions, tip and sleeve, with terminal connectors 8 and 9 extending beyond the blocks of insulating material. 85

The jack comprises a metal mounting strip 10 having secured thereto a pair of lugs 11. 90 To each lug is secured a set of contact springs. Each lug with the springs secured thereto comprises a unit, and each unit is mounted individually on the mounting strip 10. Each set of contact springs is made up 95 primarily of two main springs 12 and 13 adapted to engage the tip and sleeve respectively of the individual connectors when the plug is inserted in the jack, with the addition of auxiliary springs 16, 17 and 18 100 adapted to coöperate with springs 12 and 13 for controlling local circuits. A pair of sleeves 14 and 15 is secured in the mounting 10 for guiding the connectors into engagement with their sets of contact springs. 105 The said sleeves are separated electrically from the mounting 10 by suitable insulating washers. The contact springs are approximately U-shaped; one end of each spring is secured to a lug 11 with the other end and 110 the remaining portion thereof free. Connecting terminals 19 and 20 are formed on

the sides of the said springs and integral therewith. By the use of U-shaped springs the free ends may be long enough to insure the required flexibility and at the same time 5 may be assembled into a very compact and efficient structure.

In the use of this apparatus in connection with telephone switchboards, the jack is mounted in the lower portion of the key- 10 shelf lock rail 22 and held in position by means of suitable screws 21, as illustrated in Fig. 3. The lock rail is of wood, is placed directly under the front edge of the key shelf and extends the full length of the 15 switchboard. At each operator's position an opening is made through the lock rail, and the jack is mounted on the rear of the rail opposite such opening. A portion of the front rail is also cut away to provide an 20 opening large enough to contain the shell of the plug when the plug is inserted in the jack. As a result of this mounting arrangement, the plug, when inserted in the jack, occupies such a position that its end lies 25 flush with the front surface of the lock rail; and inasmuch as the connecting cord 23 enters the plug from the bottom, projections beyond the surface of the rail are avoided.

The allowance made in the plugs for a 30 slight interval between the individual units thereof provides a means for compensating for slight variations in the mounting centers of the individual jack sleeves 14 and 15 at the time they are assembled in the mounting plates 10. Due to this compensating feature of the plugs, wider manufacturing limits are allowable in the mounting centers of the jacks over similar types of apparatus produced heretofore, in which the individual 35 jacks and plugs were mounted on fixed centers, without impairing the operating efficiency of the apparatus.

What is claimed is:

1. A connecting plug, comprising a pair 45 of contact members, a casing inclosing a portion of the contact members, and a single means adapted to hold the casing in position and to permit a free lateral movement of the contact members.
2. In a connecting plug, a pair of contact members each comprising tip and sleeve portions separated by insulating material, additional insulating material surrounding one end of each contact member, a plurality of 55 recesses formed in said molded insulating material, an inclosure for the insulated ends of said contact members, and a single means secured to the inner walls of said inclosure adapted to coöperate with the recesses 60 formed in the molded material whereby the ends of the contact members are retained in the said inclosure but lateral movement of the said contact members is permitted.

3. The combination with a base plate provided with an aperture therein, a sleeve 65 mounted in such aperture, contact springs mounted on and extending parallel to said plate, and having free ends extending across and in perpendicular alinement to said sleeve whereby said sleeve serves to guide a 70 connector into engagement with said contact springs.

4. The combination with a base plate provided with an aperture therein, a sleeve mounted in such aperture, a set of U-shaped 75 contact springs each having one leg thereof secured to said plate and having the other leg thereof free and extending parallel to said plate, the ends of the free legs of each of said contact springs projecting across said 80 sleeve whereby said sleeve serves to guide a connector into engagement with said contact springs.

5. The combination with a base plate, of a plurality of sets of contact springs mounted thereon, a plurality of connectors adapted to coöperate with the said contact springs, means secured to said plate for guiding the said connectors into engagement with the 85 said springs, a casing inclosing the ends of said connectors, a single means for securing the said connectors to the casing and also adapted to permit sufficient lateral movement of the said connectors to compensate for variations in the mounting centers of the 90 said guiding means.

6. In a switching device, in combination, a plurality of sets of contact springs, the 95 springs of each set being secured together 100 as a unit, a base plate supporting the sets of contact springs in definite relation to apertures provided in the base plate, a casing, a plurality of plugs having one end thereof surrounded by an insulating member 105 inclosed by said casing, said insulating member having a plurality of recesses formed therein, a single means adapted to be engaged by such recesses to permit a lateral movement of the plugs and to form a connecting means for the casing, and a plurality 110 of contact members for each plug adapted to register with said contact springs when the plugs are inserted in the apertures of the base plate.

7. A connecting plug, comprising a pair 115 of contact members, a removable casing serving as a housing for a portion of the contact members, and a single means adapted to hold said casing in position and to automatically permit a free lateral movement of the contact members.

In witness whereof, I hereunto subscribe my name this 3rd day of February, A. D., 1917.

CHARLES W. LOWE.
